PELT FLESHING INSTRUMENT

Robert W. Porteous, New Westminster, British Columbia, Canada

Application October 26, 1947, Serial No. 780,882
In Canada August 11, 1947

5 Claims. (Cl. 6.9—20)

1

This invention relates to pelt fleshing instruments.

Another object is the provision of an instrument for removing surplus flesh from animal pelts without cutting or tearing the pelts.

A further object is the provision of a pelt fleshing instrument having blades which may be adjusted for different types of pelt.

Yet another object is the provision of a device of the nature described which is considerably faster and more efficient than the old hand-scraping method and which is very easy to operate.

With the above and other objects in view, the present invention consists essentially of a pelt fleshing instrument comprising a casing having an inlet opening therein through which the inner surface of a pelt may project, a plurality of blades rotatably mounted in the casing, said blades scraping the pelt when rotated, and a discharge opening in the casing spaced from the inlet opening, as more fully described in the following specification and illustrated in the accompanying drawings, in which

Figure 1 illustrates a fleshing beam,

Figure 2 is a bottom plan view of the fleshing instrument,

Figure 3 is a rear view of the instrument, and

Figure 4 is an enlarged detail of the cutting blades removed from the instrument.

Referring to Figure 1, 10 is a fleshing beam which projects horizontally from a suitable support and tapers to a nose 11. This beam is transversely rotatable about a supporting shaft 12. With most small animals, the pelt is not slit longitudinally so that it comes off more or less in tubular form and turned inside out. The pelt is then pulled on to the fleshing beam and clamped there in any suitable manner. A beam of this nature is made for each particular type of pelt so that a pelt pulled thereon is stretched fairly tightly. The instrument described below is designed to remove any flesh adhering to the pelt.

The pelt fleshing instrument consists of a casing 16 which is preferably, although not necessarily, cylindrical in shape. The casing has suitably shaped handles 17 projecting outwardly from the opposite ends thereof, and it has an inlet opening 18 formed in the bottom thereof. A plurality of blades 20 are rotatably mounted in the casing and are adapted to be rotated therein to scrape the surface of a pelt which is projected into the opening 18.

2

A block 21 in the casing 16 is mounted on a shaft 22 extending longitudinally of the casing and through the handles 17. This shaft is rotatably supported by suitable bearings, and it projects outwardly beyond the end of one of the handles 17 where it is adapted to be connected in any suitable manner to a flexible drive, shown at 23. Each blade 20 has parallel elongated slots 26 adjacent its opposite ends through which set screws 27 extend and screw into the block 21. Each blade is adjustably held in position by the set screws 27, and it projects from a longitudinal corner 28 of the block. Each blade is formed with a dull concave edge 29 at the side thereof which is projected beyond the block.

A discharge opening 32 is formed in the casing 16 at a point spaced from the inlet opening 18. This discharge opening is preferably located at a point approximately 90° from the inlet opening, and a discharge chute 33 extends outwardly from said discharge opening. This chute preferably extends outwardly from the casing 16 and curves towards one end thereof, the outer end of the chute being turned downwardly, as at 34.

A pelt is diagrammatically illustrated at 36 on the fleshing beam 10 in Figure 3. In use, the instrument is grasped by the handles 17 and drawn along the pelt on the beam. The inlet opening 18 is placed over the pelt so that the latter projects partly into the casing 16 where the concave edges 29 of the blades 28 come into contact therewith. These blades scrape the inner surface of the pelt, and as they are dull, they do not cut or tear it. The blades are shaped so that they come into contact with a relatively large area of the pelt each time the instrument is drawn over it. The flesh removed from the pelt is ejected through the discharge opening 32 and the chute 33 directs it downwardly to one side of the fleshing beam.

The blades are rotating fairly fast so that it only takes a few strokes of the instrument over the pelt completely to clean it. The fleshing beam may be transversely rotated so that the operation takes very little time or effort.

What I claim as my invention is:

1. A pelt fleshing instrument comprising a casing having an inlet opening therein through which the inner surface of a pelt may project, a plurality of blades rotatably mounted in the casing, each blade having a dull concave edge, and said blades being adapted to scrape the pelt when rotated, and a discharge opening in the casing spaced from the inlet opening.

2. A pelt fleshing instrument to be used with a fleshing beam comprising a casing having an inlet opening therein through which the inner surface of a pelt on a beam may project, a plurality of blades rotatably and adjustably mounted in the casing, each blade having a dull concave edge, and said blades being adapted to scrape the pelt when rotated, and a discharge opening in the casing spaced from the inlet opening.

3. A pelt fleshing instrument comprising a casing having an inlet opening therein through which the inner surface of a pelt may project, a block rotatably mounted in the casing, a plurality of blades mounted on the block and projecting from the longitudinal corners thereof, said blades scraping the pelt when rotated, a discharge opening in the casing spaced from the inlet opening, and a discharge chute extending outwardly from the discharge opening.

4. A pelt fleshing instrument comprising a casing having an inlet opening therein through which the inner surface of a pelt may project, a block rotatably mounted in the casing, a shaft extending from one end of the block through the end of the casing, said shaft being adapted to be connected to a flexible drive, a plurality of blades adjustably mounted on the block and projecting from the longitudinal corners thereof, said blades scraping the pelt when rotated, a discharge opening in the casing spaced from the inlet opening, and a discharge chute extending outwardly from the discharge opening.

5. A pelt fleshing instrument to be used with a fleshing beam comprising a casing having an inlet opening therein through which the inner surface of a pelt on a beam may project, a handle on each end of the casing, a block rotatably mounted in the casing, a shaft extending from one end of the block through the casing to one of the handles, said shaft being adapted to be connected to a flexible drive, a plurality of blades adjustably mounted on the block and projecting from the longitudinal corners thereof, and each blade having a dull concave edge, and said blades being adapted to scrape the pelt when rotated, a discharge opening in the casing spaced from the inlet opening, and a discharge chute extending outwardly from the discharge opening.
